UNITED STATES PATENT OFFICE.

WALTER E. BARNARD, OF HARTFORD, CONNECTICUT, ASSIGNOR TO UNDERWOOD TYPEWRITER COMPANY, OF NEW YORK, N. Y., A CORPORATION OF DELAWARE.

COPY-HOLDER.

1,226,939.

Specification of Letters Patent.

Patented May 22, 1917.

Application filed October 30, 1911. Serial No. 657,409.

To all whom it may concern:

Be it known that I, WALTER E. BARNARD, a citizen of the United States, residing in Hartford, in the county of Hartford and State of Connecticut, have invented certain new and useful Improvements in Copy-Holders, of which the following is a specification.

My invention relates to copy holders, and is particularly related to those which are mounted on the frame of the typewriter.

In the preferred form herein illustrated, it comprises a bracket which is held on the front of an Underwood typewriter by the same screws which hitherto have been used to hold on the front plate of the machine. A clamp on this bracket supports a table on which the copy lies flat and beneath which are mounted rolls which project to or slightly above the surface of the table. Above these are mounted other rolls which coöperate with the first rolls in moving forward the copy. These upper rolls may be turned either by a knob in either direction, or by means of a handle working through a pawl and ratchet wheel, in the direction in which it is desired to normally feed the copy. This handle automatically moves forward the copy the space of one line every time the handle is pressed.

There may be provided also a guide for the eye to follow, which may be adjusted across the table, and which is clamped to a rod at the side of the table in any desired position.

Among the advantages of my invention is that the copy holder is held on by the same screws which hold on the front plate of the Underwood typewriter, so there are no loose parts to be lost and only an ordinary screw driver is needed to put the holder in place. The work is positively held at the right distance from the eyes in the copy holder, and is always moved forward just the right amount for each line. The holder itself is easily swung back on its clamp out of the way when not in use.

Other features and advantages will hereinafter appear.

In the accompanying drawings, 50
Figure 1 is a perspective view of my improved copy holder, showing it attached to the front of a typewriter, most of the typewriter being broken away for the sake of clearness. 55

Fig. 2 is a rear view, showing the position of the rolls.

Fig. 3 is a view showing the ratchet when it has just moved forward the work one line-space. 60

Fig. 4 shows the ratchet and other parts when the pawl is disengaged from the ratchet.

Fig. 5 is a section showing how the guide is attached to its rod. 65

1 is a suspension bar on which are mounted at each end brackets 2 and 3 carrying a table 4, on which the matter to be copied is laid. Other brackets 5 and 6 rise at the ends of said suspension bar, and serve as 70 bearings for the shafts of upper rolls 7 and lower rolls 8. The lower rolls are loose on their shaft 9 and are spaced along it at intervals by spacing tubes 10. This shaft is mounted in elongated bearings 11 in which 75 it is free to play, and is pressed normally upward toward the upper portion of said bearings by springs 12, so as to bear against the bottoms of the upper rolls 7. The upper rolls aforesaid, are fast on their shaft 13, 80 and are adapted to be turned with it by means of a knob 14 at one end of the shaft.

On the opposite end of the shaft 13 is a loose wheel 15, carrying a handle 16 and a pawl 17. This latter pawl engages with a 85 ratchet 18 on said shaft 13, and so, whenever the handle is moved, turns said shaft 7 with its rolls in one direction.

The movement of the handle 16 is limited by stops 19 and 20 located on the idle wheel, 90 which are arranged to strike against a pin 21 on the bracket 5, and these stops are so arranged that one full throw of the handle 16 from one limit to the other, will exactly move forward the paper between the rolls 95 one line-space.

The pawl 17 is drawn down normally into contact with the ratchet wheel by means of

a spring 22 anchored to the pin 21, and on the end of the pawl is arranged a cam surface 23, which is adapted whenever it strikes pin 21, to raise said pawl clear of the ratchet wheel, so that the shaft and rolls may be turned freely by knob 14 in either direction.

In order to guide the eye in reading the copy, a guide 24 extends across the table 4, and is mounted on a rod 25 by means of a

10 clamp 26, so that it may be adjusted in any convenient position. This clamp is arranged so as not to mar the surface of the rod 25, and comprises a main body 27 in which a screw 28 moves freely carrying on its end 15 a ring 29 embracing the rod 25. This ring 29 may be drawn outward by means of a thumb nut 30 working on the screw 28, and bearing against the main body of the clamp, to lock the guide on the rod.

20 The rod 25 itself is mounted in a small bracket 31 on bracket 3, and has a flat side 32 which bears against the body of bracket 3, so as to hold the rod substantially parallel to the table. The rod 25 is so arranged that 25 it may be easily slipped in and out of the small bracket 31, so that it may be removed whenever not needed.

In order to prevent the paper from catching beneath the rolls or in the supporting 30 mechanism of them, the upper end of the table is extended as by fingers or strippers 33 passed between the rolls, so as to form strippers to carry the paper clear of them. Also an upper shield 34 is provided to cover the 35 upper rolls, and to keep dust out of them and paper from getting entangled with them.

In Fig. 4, a sheet of paper is shown at 35 lying between the rolls passing under the guide 24 and outwardly beyond the strippers 33.

The rolls themselves are preferably covered with a layer of cork composition as shown at 36 which enables them to grip the paper easily.

45 It will therefore be apparent that it is impossible for the paper to get entangled in the mechanism and the copy will require no attention beyond the operation of the handle when once properly set.

50 To best use my copy holder, it is attached to the typewriter. For this purpose, the suspension bar 1 is extended to form a flat tongue 37 which is gripped in a socket formed by the flat arms 38 of a bracket 39.

55 These arms are made resilient by extending a slot 40 from the socket so that the arms 38 can be closed on flat tongue 37 by means of a thumb screw 41. The suspension bar is thus restricted to swing in a horizontal plane.

60 An arm 42 of said bracket 39 extends upward along the front of the Underwood typewriter, and is pierced with holes through which the screws 43 may pass. These screws are the ones that are ordinarily

employed to hold the front plate 44 on the 65 frame 45 of an Underwood typewriter. To attach the copy holder the screws are removed, the bracket placed in position in front of the plate, and the screws then reinserted through both bracket and face plate. 70 The bracket arm 42 is preferably somewhat cut away at 46 to give free access to the lock release button 47.

It will be seen that my copy holder may be easily adjusted at the most convenient 75 angle for work, or may be swung one side completely out of the way, as shown in Fig. 1, and is easily locked by screw 41 in either position. Furthermore, if it is removed from the machine for any purpose, there are 80 no loose parts of either machine or holder to lose while stored.

Variations may be resorted to within the scope of the invention, and portions of the improvements may be used without others. 85

Having thus described my invention, I claim:

1. In combination, in a copy holder, a suspension bar, brackets on said bar, feeding means on said brackets, a table, a table-bearing bracket, a small bracket beneath said table-bearing bracket, a rod adjustable in said small bracket, and an eye guide mounted on said rod and over said table. 90

2. In combination, in a copy holder, a suspension bar, brackets on said bar, feeding rolls on said brackets, a forwardly and downwardly extending table, a bracket extending horizontally from said table and secured to said suspension bar, a small bracket 100 attached to the underside of said horizontal bracket, a flat-sided rod sliding in said small bracket, a right-angled extension to said rod, and an eye-guide adjustably mounted in said extension over said table. 105

3. In combination, in a copy holder, a suspension bar, brackets on said bar, rolls mounted yieldingly in said brackets, means for imparting rearward feed to said rolls, a downwardly and forwardly extending copy 110 supporting table arranged in line with the bight of said rolls, a bracket for supporting said table, attached to said suspension bar, a rod carried by said last named bracket, and an eye-guide carried by said rod. 115

4. In a copy holder, a frame, a copy table, rolls to feed copy across said table, a shaft supported in the frame carrying said rolls, a knob for turning said shaft, a ratchet wheel for turning said shaft in one direction, a spring operated pawl pivoted on an idle wheel on said shaft, a stop on the frame, co-operating stops on the idle wheel to engage said first stop to limit the throw in both directions of said idle wheel, and a handle on said idle wheel to rotate it to move said shaft by said pawl, said pawl having a cam face to engage said stop on the frame to disen-

gage said pawl from said ratchet when said handle is at a limit of its throw.

5. In a copy holder, a table, rolls fixed on a shaft above said table, means pivoted on the said shaft whereby said rolls may be fed backward, rolls extending to the surface of said table loose on a shaft below said table, spacing means for said rolls, elongated bear-

ings for said shaft, and springs pressing upon said lower shaft in the spacing provided between its rolls, to press said rolls against said upper shaft. 10
